[57] CLAIM

The ornamental design for a set of retractable ear plugs, as shown and described.

DESCRIPTION

FIG. 1 is a side elevational view of a set of retractable ear plugs, showing my new design;

FIG. 2 is an elevational view of the opposite side thereof;

FIG. 3 is a bottom plan view thereof;

FIG. 4 is a front elevational view of the reel portion of the device;

FIG. 5 is a top plan view of the device as shown in FIG. 3;

FIG. 6 is an isometric view of one of the ear plugs. The cord has been shown fragmentarily in FIGS. 1, 2, 3 and 5 to indicate indeterminate length.

FIG. 1

FIG. 2

FIG. 3

FIG. 4

FIG. 5

FIG. 6
